(57) **CLAIM**

The ornamental design for a display screen or portion thereof with animated graphical user interface, as shown and described.

DESCRIPTION

FIG. 1 is a front view of the first image in a sequence of a display screen or portion thereof with animated graphical user interface.

FIG. 2 is a front view of the second image;

FIG. 3 is a front view of the third image;

FIG. 4 is a front view of the fourth image;

FIG. 5 is a front view of the fifth image;

FIG. 6 is a front view of the sixth image;

FIG. 7 is a front view of the seventh image; and,

FIG. 8 is a front view of the eighth image.

The rectangular space around the text within the shading in FIGS. 2-8 forms no part of the claimed design. The broken lines showing the display screen, the electronic device, and portions of the graphical user interface illustrate environment and form no part of the claimed design. The subject matter in this patent includes a process or period in which an image changes into another image. This process or period forms no part of the claimed design.

1 Claim, 8 Drawing Sheets
